Primary Examiner—Stella Reid*Assistant Examiner*—I Simmons*Attorney, Agent, or Firm*—Hayes Soloway Hennessey Grossman & Hage PC[57] **CLAIM**

I claim the ornamental design for a multi-well plate, as shown and described.

DESCRIPTION

FIG. 1 is a perspective view of a multi-well plate showing my new design;

FIG. 2 is a top plan view of the multi-well plate of FIG. 1; FIG. 3 is a bottom plan view of the multi-well plate of FIG. 1;

FIG. 4 is a front elevational view of the multi-well plate of FIG. 1;

FIG. 5 is a rear elevational view of the multi-well plate of FIG. 1;

FIG. 6 is a left side elevational view of the multi-well plate of FIG. 1;

FIG. 7 is a right side elevational view of the multi-well plate of FIG. 1;

FIG. 8 is a perspective view of a second embodiment of a multi-well plate showing my new design;

FIG. 9 is a top plan view of the multi-well plate of FIG. 8; FIG. 10 is a bottom plan view of the multi-well plate of FIG. 8;

FIG. 11 is a front elevational view of the multi-well plate of FIG. 8;

FIG. 12 is a rear elevational view of the multi-well plate of FIG. 8;

FIG. 13 is a left side elevational view of the multi-well plate of FIG. 8; and,

FIG. 14 is a right side elevational view of the multi-well plate of FIG. 8.
